CLAIM

The ornamental design for a display screen with graphical user interface, as shown and described herein.

DESCRIPTION

The patent or application file contains at least one drawing executed in color. Copies of this patent with color drawing(s) will be provided by the Office upon request and payment of the necessary fee.

The sole FIGURE is a front view of a display screen with graphical user interface of my new design.

The broken line showing a display screen illustrates portions of the article and forms no part of the claimed design.
